US00D883380S

(12) **United States Design Patent** (10) **Patent No.:** **US D883,380 S**
Cai (45) **Date of Patent:** **** May 5, 2020**

(54) **BOARD**

(71) Applicant: **AUTEL INTELLIGENT TECHNOLOGY CORP., LTD.**,
 Shenzhen, Guangdong (CN)

(72) Inventor: **Zhenyu Cai**, Guangdong (CN)

(73) Assignee: **AUTEL INTELLIGENT TECHNOLOGY CORP., LTD.**,
 Shenzhen (CN)

(**) Term: **15 Years**

(21) Appl. No.: **29/654,014**

(22) Filed: **Jun. 20, 2018**

(30) **Foreign Application Priority Data**

Dec. 25, 2017 (CN) 2017 3 0666480
 (51) LOC (12) Cl. **19-06**
 (52) U.S. Cl. **USPC D19/113**

CLAIM

The ornamental design for a board, as shown and described.

DESCRIPTION

FIG. 1 is a perspective view of a board showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 5 Drawing Sheets
